United States Patent Office

Des. 180,218

Patented May 7, 1957

180,218

DRAWING TABLE

Manuel M. Alvarez, Los Angeles, Calif., assignor of fifty
percent to James E. Gonzales, Van Nuys, Calif.

Application February 15, 1956, Serial No. 40,179

Term of patent 3½ years

(Cl. D33—14)

Fig. 1

Fig. 2

Fig. 3

Fig. 4

Fig. 1 is a top perspective view of a drawing table showing my new design, with the top in raised position;

Fig. 2 is an elevational view taken from the side opposite that shown in Fig. 1, with the top closed;

Fig. 3 is an elevational view taken from the right of Fig. 2; and

Fig. 4 is an elevational view taken from the left of Fig. 2.

I claim:

The ornamental design for a drawing table, as shown.
